FIG. 1.

Design No. 553.—
Just Bury applied to M. D. Brown et al. Design a. 1003. Date of p. 1003.

FIG. 2.

Des. 553

Jacob Beesley, of ^{the District of} Spring Garden, Pa.

Assignor to

William P. Cresson, of Spring Garden, aforesaid

Letters Patent No. 553 Dated April 19th 1853.

mmmm

The schedule referred to in these Letters Patent and making part of the same

mmmmmm

To all whom it may concern:

Be it known, that I, Jacob Beesley, of the District of Spring Garden, in the County of Philadelphia, and State of Pennsylvania, have invented or produced a new and original design to ornament a stove for cooking, and I do hereby declare that the following is a full and exact description of the same.

Fig: 1. represents the side of the stove including the oven and wood doors, the side being ornamented on the outer edge by several beads as at a, a, a, a, the wood door is ornamented in the centre with raised rays emanating from a centre as at b, b, b, around which is a groove ornamented with a small rosette as at c, c, c, c, outside of which are some bead work as at d, d, d, d, outside of which is bead work of a og shape as at e, e, e, e, the oven door is ornamented around its outer edge with og, bead work, inside of which is rope beading as at a, a, a, a, inside of this is grooved beading ornamented with rosettes as at b, b, b, b, b, inside of same is raised rays, emanating from a rosette as at c, c, c, c, - we sometimes use this same door without the polygon corner, the smaller oven door is ornamented the same as the large one except the rosette in the centre being different as at f.

Des. 553

Fig: 2. Represents the bottom plate, being ornamented with fluted bead work and rosettes as at a, a, a, a, a, —

What I claim as my invention and wish to secure by Letters Patent is the combination and arrangement of the ornamental forms and figures, represented in the accompanying drawings and forming together an ornamental design for a cooking stove.
